W. A. BECKER.
COMBINATION FEED HOPPER AND POULTRY FOOD CARTON.
APPLICATION FILED APR. 19, 1915.

1,189,779.

Patented July 4, 1916.

Walter A. Becker.

INVENTOR.

UNITED STATES PATENT OFFICE.

WALTER A. BECKER, OF NORTH CHATTANOOGA, TENNESSEE, ASSIGNOR OF ONE-HALF
TO S. RUSSELL DOW, OF CHATTANOOGA, TENNESSEE.

COMBINATION FEED-HOPPER AND POULTRY-FOOD CARTON.

1,189,779.

Specification of Letters Patent.

Patented July 4, 1916.

Application filed April 19, 1915. Serial No. 22,345.

To all whom it may concern:

Be it known that I, WALTER A. BECKER, a citizen of the United States, residing at North Chattanooga, in the county of Hamilton and State of Tennessee, have invented a new and useful Combination Feed-Hopper and Poultry-Food Carton, of which the following is a specification.

The object of my invention is to provide 10 a device which may be stamped from a single blank and folded to form a poultry-food carton, and which may be readily converted by the user to a poultry feed hopper, thus increasing the usefulness of the device 15 by reason of its convenience and comparatively small cost of manufacture.

I attain the objects of my invention by the mechanism illustrated in the accompanying drawings, in which—

20 Figure 1 is a blank showing the form of the device before it is folded for use; Fig. 2 is a perspective view of the device as a feed-hopper; Fig. 3 is a section taken on an approximate vertical median line through Fig. 2; and Fig. 4 is a perspective view of the device as a shipping carton.

Like characters of reference indicate like parts throughout the several views.

Referring to the accompanying drawings, 30 I provide a blank such as illustrated in Fig. 1, having a side a^1 , a front b , a side a integrally formed with the back and front, and a back c , having an edge strip a^2 adapted to be glued to side a^1 when the blank is 35 folded into box form.

On the top portion of the blank I provide a cover flap j having an inwardly folding edge flap h . I also provide side top flaps X^1 . Integral with back c is a suspending 40 flap m , having an aperture n , to permit of suspending the device from a nail when in use as a feed hopper. Flap m is provided with a tongue k , adapted to be inserted in a slot k^1 , provided in cover flap j , when the 45 device is folded in carton form for shipping purposes.

On the lower portion of the blank, I provide an integral base w , forming an extension of back c , and having spaced slots z^1 . 50 Integral with base w is an upturned flap portion u , having notched ears f , adapted to engage in slots f^1 in sides a and a^1 , respectively, as illustrated. When the device is employed as a carton, extended portions p 55 and p^1 conceal the hopper, side flaps s en-

gage in apertures left by folding in flaps e , e , and flaps b^3 engage in slots b^1 , as illustrated in Fig. 4. A central tongue O engages in slots b^2 , as illustrated in Figs. 2 and 4.

In order that the device may operate as a feed hopper, flap d on front b is pressed inwardly to an inclined position, portion d^1 is bent horizontally, and tongue g is inserted through slots g^1 in back c , as indicated in Fig. 3, the hook form of the tongue serving to lock it in place.

The carton folds to make a box by gluing edge strip a^2 to side a^1 . Flaps e are then folded inward. Portion d is then pressed into inclined position, portion d^1 bent into horizontal position, and tongue g inserted first through the upper and then back through lower slots, indicated by g^1 , its hook shape serving to effect a locking of the 75 device in place. Tongue O is folded forward and upward, and engaged in slots b^2 , as illustrated in Fig. 4. Side extension flaps X are folded inward, overlapping base w , tongues z being inserted in slots z^1 in base w , to secure them in place, and hooked tongues f are inserted in slots f^1 , thus locking the 80 bottom of the carton into engagement as illustrated.

When used as a shipping carton, flaps s 85 are inserted into apertures left by the turning in of flaps e , and flaps b^3 are inserted in slots b^1 . Top flap j is folded so that its edge flap h may be inserted into the carton, suspending flap m is folded forward and its tongue k engaged in slot k^1 , as illustrated in Fig. 4.

To convert the device from a poultry-food carton into a feed hopper, flaps b^3 are pulled out from slots b^1 , and portions of the 95 device exterior to the scored or perforated lines O^2 and O^3 are torn off, leaving the bottom portion of the device open for feeding purposes, while it is retained in the desired position by the engagement of the central tongue O in slots b^2 , and by the locking of hooked tongues f in slots f^1 . To hang 100 up, pull out flap m from slot k^1 , and suspend the device from a nail which may be inserted through aperture n .

The device may be manufactured solely 105 as a feed-hopper, the same blank being employed, the portions adjacent to tongue O being torn downward on the lines O^3 , and then folded inward on the lines O^2 (instead 110

of being detached), as illustrated in Fig. 3, bringing portion p^1 into contact with α which serves to lock it in place, by pressing against edge indicated by p^2 in Fig. 1; the device otherwise being arranged as heretofore described.

The blank from which the device is constructed may be stamped out of cardboard or metal; and the cardboard may be plain or 10 paraffined, either inside, outside, or both.

What I claim is:

1. A combination feed hopper and poultry-food carton formed from a single blank having front, side and back portions, cover 15 flaps, base flaps and a lower flap portion normally forming a portion of the front of the carton and adapted to be disengaged from its normal position and bent inwardly toward the back of the carton and having 20 means for retaining it in engagement with the back of the carton with its main bottom edge spaced apart therefrom to provide a passage for the downward flow of feed narrower than the main body of the 25 carton, whereby the device may be converted into a poultry food carton.

2. A combination feed hopper and poultry-food carton formed from a single blank comprising integral front, side and back 30 portions, cover and suspending flap portions, base flap, hooked tongue extension portions adapted to lock the blank in carton form,

readily detachable side portions adapted to be torn off to convert the device into a feed hopper, and a tongue inclined flap portion 35 adapted to lock into the back of the carton to retard the downward flow of feed into the feed hopper, substantially as set forth.

3. A feed hopper formed from a single blank and comprising front, side and back 40 portions, a cover portion integral with the front, a suspending flap integral with the back, a tongued feed hopper flap integral with the front and adapted to be bent inwardly toward the back of the carton to afford a narrow passage between the bottom edge thereof and the back of the carton and having a tongue to engage in slotted portions of the back, side extension flaps having inwardly bendable tongues, a base having 45 a hooked tongue engageable in slotted portions of the front of the blank, and having hooked tongues engageable in slotted portions of the sides of the blank, and portions adjacent the central tongue adapted to 50 be detached from engagement with the tongue and to be folded inward to lock against the tongues of the inwardly folded side extension flaps, substantially as shown and described.

WALTER A. BECKER.
